UNITED STATES PATENT OFFICE.

HUGO C. WELL, OF NEW YORK, N. Y.

CARBURETER.

1,216,027.

Specification of Letters Patent. Patented Feb. 13, 1917.

Application filed January 11, 1916. Serial No. 71,482.

To all whom it may concern:

Be it known that I, HUGO C. WELL, a subject of the German Emperor, and a resident of the city of New York, borough of Bronx, 5 in the county of Bronx and State of New York, have invented a new and Improved Carbureter, of which the following is a full, clear, and exact description.

My invention has for its object to provide 10 a carbureter with a wick for conveying by capillary attraction a hydrocarbon to a passage where the air passing therefrom will entrain the hydrocarbon.

Another object of the invention is to provide 15 means for regulating the area of the air passage, as well as the area of another air passage through which air may pass to be subsequently mixed with the air carrying the hydrocarbon.

20 Another object of the invention is to provide novel valve means for regulating the area of the two passages.

Still other objects of the invention will appear in the following specification, in 25 which the preferred form of my invention is disclosed.

In the drawings similar reference characters denote similar parts in all the views, in which—

30 Figure 1 is a sectional view on the line 1—1 of Fig. 2;

Fig. 2 is a sectional view on the line 2—2 of Fig. 1;

Fig. 3 is a view of the rotatably mounted 35 valve member;

Fig. 4 is a fragmentary view showing the indicating means for determining the position of the rotary valve member; and

Fig. 5 is a view showing the stationary 40 valve member, which serves as a seat for the wick.

By referring to the drawings, it will be seen that the carbureter is constructed with a body 10 having a passage 11 with converging walls 12 for mixing an explosive mixture 45 with air, in a manner which will hereinafter be described. This body 10 has a depending wall 13 and a depending threaded portion 14 with which meshes a thread 15 on a body

50 member 16, this body member 16 having a circular wall 17 disposed concentrically with the wall 13 and spaced therefrom, to form a fountain 18 for the hydrocarbon. The member 16 at the bottom of its wall 17 is disposed 55 inwardly at 19, forming a bottom for the fountain 18, the bottom 19 being, however,

spaced from the bottom of the circular wall 13 to form a passage 20 which leads to an annular canal 21 formed by the wall 13 and a concentric wall 22 which extends upwardly 60 from the bottom 19 of the member 16. This member 16 also has a circular wall 23 which extends upwardly from its bottom member 19, this circular wall 23 being substantially concentric with the wall 22, to form a passage 24 around a central passage 25 with which the member 16 is provided and which is formed by the wall 23. The bottom 19 of the member 16 has openings 26 which lead to the passage 24, the bottom 19 being also 65 provided with a central opening 27 which leads to the passage 25, the wall 23 adjacent the opening 27 having a seat 28 against which is disposed a tube 29 to which is secured a rotary valve member 30. 70

This rotary valve member 30 is disposed on a seat 31 at the top of the wall 22, and is held in place by a valve member 32, which is disposed against the top of the rotary valve member 30 and is provided with a 80 thread 33 which meshes with a thread 34 in the wall 22.

The valve member 32 has a set of valve openings 35 which are disposed over the passage 24, the valve member 32 being also 85 provided with another set of valve openings 36 which are disposed over the passage 25, the valve openings 36 being staggered radially relatively to the valve openings 35. The valve member 30 has valve openings 37, each 90 of which extends not only over the passage 24, but also over the passage 25, so that when this valve member 30 is rotated relatively to the valve member 32, the valve member 30 at its valve openings 37 will close one set 95 of the valve openings with which the valve member 30 is provided, while it opens the other set of valve openings in the valve member 32. The valve openings 37 and also the valve openings 35 and 36 are preferably provided with radially extending sides. 100

Disposed in the canal 21 there is a wick 38, this wick 38 extending inwardly and over the valve member 32, so that the wick will be disposed above the passage 24, but I prefer not to extend the wick above the passage 25. With this construction, the air which is drawn upwardly in the passage 24 by the operation of the piston in an internal combustion engine, will be drawn through the 110 wick 38, and as this wick 38 extends below the level of the hydrocarbon in the fountain

- 18, the wick will be saturated with hydrocarbon above the passage 24, and this hydrocarbon will be entrained with the air, which air charged with hydrocarbon will be directed inwardly by the converging side walls 12 at the passage 11, and will be mixed with air passing upwardly in the central passage 25. There may be any desired number of openings 39 in the wall 13 to make certain that the wick 38 above the passage 24 is saturated with the hydrocarbon at all times, and the level of the hydrocarbon in the fountain 18 may be maintained by any of the well known means.
- 15 Secured to the tube 29, there is an arm 40 which extends laterally and has secured to it a finger 41 which with a scale 42 may be used to determine the position of the valve member 30 relatively to the valve member 32.
- 20 The hydrocarbon is led to the fountain 18 through an opening 43 in the wall 17.
- Having thus described my invention, what I claim as new and desire to secure by Letters Patent, is:
- 25 1. In a carbureter, a casing with two passages, one disposed at a greater distance from the center than the other, a valve member disposed across the two passages and provided with two valve openings, one at 30 each passage, the valve openings being disposed in different radial planes, a rotatable valve member disposed against the first valve member and having a radially extending valve opening for uncovering one 35 valve opening in the first valve member as the other valve opening in the first valve member is closed by the second valve member beyond its valve opening and means to supply one of the passages with a hydrocarbon.
- 40 2. In a carbureter, a casing having two concentric passages, a valve member disposed across the passages and provided with two concentric sets of valve openings, one 45 set of valve openings being disposed at a greater distance from the center, and being staggered relatively to the other set of valve openings, a rotatable valve member disposed against the first valve member and having 50 radially extending valve openings for opening one set of valve openings while closing the other set of valve openings in the first valve member, and means to supply one of the passages with a hydrocarbon.
- 55 3. In a carbureter, a casing having two concentric passages, a valve member disposed across the passages and provided with two concentric sets of valve openings, one 60 set of valve openings being disposed at a greater distance from the center, and being staggered relatively to the other set of valve openings, a rotatable valve member disposed against the first valve member and having 65 radially extending valve openings for opening one set of valve openings while closing

the other set of valve openings in the first valve member, means to rotate the second mentioned valve member relatively to the first valve member, and means to supply one of the passages with a hydrocarbon.

4. In a carbureter, a casing having two concentric passages, a valve member having two concentric sets of valve openings, one set of valve openings being disposed at a greater distance from the center and being staggered relatively to the other, a rotatable valve member disposed between the first valve member and the surface of the casing at the two passages therein, a tube secured to the rotatable valve member and extending in 80 the inner passage in the casing, means to rotate the tube, and means to supply one of the passages with a hydrocarbon.

5. In a carbureter, a casing with an outlet passage, a valve member disposed across the 85 passage and provided with two valve openings disposed in different radial planes and leading to the outlet passage, there being two inlet passages in the casing leading one to each valve opening, a rotatable valve member disposed against the first valve member and having a radially extending valve opening for uncovering one valve opening in the first valve member as the other valve opening in the first valve member is closed by the second valve member 90 beyond its valve opening, and means to supply one of the inlet passages with a hydrocarbon.

6. In a carbureter, a casing having a passage with two walls spaced apart at one side of the passage, the two walls forming a canal, there being an opening in the outer wall leading to the canal, means to supply a hydrocarbon to the canal through the 100 opening, a wick disposed across the passage and extending into the canal, and valve means adjacent the wick and disposed between the inlet to the passage and the wick.

7. In a carbureter, a casing having a fountain and a passage with two walls spaced apart between the fountain and the passage to form a canal, there being an opening adjacent the top of the wall leading from the canal to the passage and an opening adjacent the bottom of the wall leading to the fountain, a wick disposed across the passage and through the first opening, down in the canal, and valve means disposed adjacent the wick and between the inlet to the passage and the wick.

8. In a carbureter, a casing having a fountain and a passage with two concentric walls spaced apart, separating the fountain from the passage to form a canal, there being an 125 opening adjacent the top of the wall leading from the canal to the passage, and an opening adjacent the bottom of the wall leading to the fountain, a wick disposed across the passage and through the first 130

opening and down in the canal, and valve means disposed adjacent the wick and between the inlet to the passage and the wick.

9. In a carbureter, a casing having two concentric passages, a fountain and two concentric walls spaced apart separating the outer passage from the fountain, there being an opening adjacent the top of the inner concentric wall and an opening adjacent the bottom of the outer concentric wall, a wick disposed across the outer passage and extending through the opening in the inner wall and down between the two walls, and valve means disposed adjacent the wick and between the inlet to the passage and the wick.

10. In a carbureter, a casing having three substantially concentric walls forming an inner passage, a passage therearound and an annular canal leading to the second passage, additional wall members which with the outer concentric wall form a fountain, there being an opening adjacent the bottom of the outer concentric wall affording communication between the fountain and the annular canal, a wick disposed across the second passage and extending down in the annular canal, the casing having an outlet the walls of which converge from the wick to direct the gases passing through the wick in the direction of the gas passing through the first passage.

11. In a carbureter, a casing having three substantially concentric walls forming an inner passage, a passage therearound and an annular canal leading to the outer passage, additional wall members which with the outer concentric wall form a fountain, there being an opening adjacent the bottom of the outer concentric wall affording communication between the fountain and the annular canal, a wick disposed across the outer passage and extending down in the annular canal, a valve member disposed across the two passages and provided with two concentric sets of valve openings, one set of valve openings being disposed at the first passage and the other set of valve openings being staggered relatively to the first set of valve openings and being disposed at the second passage, a rotatable valve member disposed against the first valve member and having radially extending valve openings for closing one set of valve openings in the first valve member as the other set of valve openings in the first valve member is opened.

12. In a carbureter, a casing having three substantially concentric walls forming an inner passage, a passage therearound and an annular canal leading to the outer passage, additional wall members which with the outer concentric wall form a fountain, there being an opening adjacent the bottom of the outer concentric wall affording communication between the fountain and the annular

canal, a wick disposed across the second passage and extending down in the annular canal, a valve member having its body spaced from the casing but secured relatively thereto, a rotatable valve member disposed between the first valve member and the casing, and means for rotating the rotatable valve member.

13. In a carbureter, a casing member having an outlet and a wall extending therefrom, another casing member having a plurality of walls extending in the direction of the outlet and disposed at the side of the first wall, means to secure the two casing members together, the last mentioned walls being spaced from each other and from the first wall, thereby forming passages, there being openings affording communication between the passages, atomizing means at the junction of two of the passages, and air inlet means for one of the said two passages.

14. In a carbureter, a casing member having an outlet and a wall extending therefrom, another casing member having a plurality of walls extending in the direction of the outlet and disposed at the side of the first wall, means to secure the two casing members together, the last mentioned walls being spaced from each other and from the first wall, thereby forming passages, there being openings affording communication between the passages, atomizing means at the junction of two of the passages, air inlet means for one of the last two mentioned passages, and additional air inlet means for another of the passages, the first casing member at its outlet extending from the plane of one of the passages having air inlet means in the general direction of the plane of the passage having the other air inlet means.

15. In a carbureter, a casing with an outlet passage, a valve member across the passage and provided with two staggered valve openings one disposed at a greater distance from the center of the valve member than the other, and both leading to the outlet passage, there being two concentric inlet passages in the casing one leading to each valve opening, a rotatable valve member disposed against the first valve member and having a radially extending valve opening for uncovering one valve opening in the first valve member as the other valve opening in the first valve member is closed by the second valve member beyond its valve opening and means to supply one of the inlet passages with a hydrocarbon.

16. In a carbureter, a casing with an outlet passage and a valve member disposed across the passage and provided with two staggered valve openings one disposed at a greater distance from the center of the valve member than the other, there being two concentric inlet passages in the casing one lead-

1
ing to each valve opening, a rotatable member disposed against the first valve member and having a radially extending valve opening for uncovering one valve opening in the first valve member as the other valve opening in the first valve member is closed by the second valve member beyond its valve opening, a tube in one of the inner passages to which the second valve member is secured, and means to rotate the tube and means to supply one of the inlet passages with a hydrocarbon.

10 17. In a carbureter, a casing having three substantially concentric walls forming a passage, a passage therearound, an annular canal leading to the second passage, addi-

20 tional wall members which with the outer concentric wall form a fountain, there being an opening adjacent the bottom of the outer concentric wall affording communication between the fountain and the annular canal, and a wick disposed across the second passage and extending down into the annular canal.

25 In testimony whereof I have signed my name to this specification in the presence of two subscribing witnesses.
